UNITED STATES PATENT OFFICE.

HERMAN C. HOLL, OF LAKEWOOD, OHIO.

CAMP STOVE.

Application filed June 7, 1924. Serial No. 718,544.

To all whom it may concern:

Be it known that I, HERMAN C. HOLL, a citizen of the United States, residing at Lakewood, in the county of Cuyahoga and 5 State of Ohio, have invented certain new and useful Improvements in Camp Stoves, of which the following is a specification.

This invention relates to improvements in camp stoves, having for an object to provide a collapsible structure which may be 10 entirely housed within the chimney or flue pipe.

Another object is to provide a collapsible camp stove having a sectional cast metal 15 grate and sectional cast metal top plate whereby to form an unusually efficient stove.

A further object is to construct a camp stove having a chimney or flue pipe mounting 20 slidable cover plates one of which may be utilized as a damper.

It is likewise an object to construct a collapsible camp stove, so formed as to be easily assembled and to occupy a minimum amount of space when knocked down and housed for 25 transportation.

Other objects will be in part obvious and in part pointed out hereinafter.

In order that the invention, its construction and functioning may be readily understood by others, I have in the accompanying 30 illustrative drawings and in the following specification and claims based thereon, set out the preferred embodiment thereof.

Figure 1 is a perspective view of the camp 35 stove assembled;

Figure 2 is a detail view of the upper closable end of the smoke stack;

Figure 3 is a detail perspective view showing the method of assembling the parts making 40 up the fire-box;

Figure 4 is a cross sectional view showing the relation of the two plates forming the cover of the fire-box;

Figure 5 is a substantially central vertical 45 longitudinal sectional view of the fire-box, and

Figure 6 is a detail perspective view of the manner in which the plates forming the fire-box base are connected.

Having particular reference to the drawings, throughout which similar characters of reference designate similar parts, this improved collapsible camp stove may be broadly stated as comprising a body portion 50 or fire-box and top plate, arranged upon supporting legs, and provided with a sec-

tional fire grate, all of which are separable and compactly receivable in a smoke-stack or flue-pipe, this flue-pipe serving as a carrier and having a handle secured thereto. 60

The body portion or fire-box comprises a bottom or base made up of a pair of elongated sheet metal plates 10 overlapping at their adjacent edges and separably connected through providing a set of fingers 11, which 65 take over the edges of the plates as shown. Each plate has its outer edge turned or bent upwardly to form a flange 12 whose function is to retain against outward shifting, the bottom portion of the adjacent side and 70 end walls or members. As shown, the upturned portions at the front end are merely in the form of lugs or stops 13 which secure the door frame in position.

A pair of sheet metal side members or 75 plates 14 is arranged with the lower edges disposed behind the flanges 12 carried by the base plate 10. The ends of these side plates 14 are separably connected with the door frame and rear end member through 80 forming upon the opposite vertical edges of these end members 15, inwardly extending flanges 16 which snugly contact with the outer surfaces of the sides as shown in Figures 3 and 5 of the drawings. Separable 85 connection is provided through forming bayonet slots 17 in each end of each side plate to receive headed studs or pins 18 carried by the vertical flanges 16 of the end members. Figures 3 and 5 clearly illustrate 90 this point. The vertical flanges carried by the end members 15 are disposed between the flanges carried by the base plates 10 and the bayonet slotted ends of the side plates, thus providing a rigid self supporting structure. As a further means for maintaining 95 rigidity, I form sets of upstanding lugs 19 upon the base plates 10 to snugly engage the inner lower faces of the side plates as illustrated in Figure 3.

The front end member 15 mounts a pair of superposed doors, the lower one permitting of access to the ash pit and the upper one being designed to allow feeding of fuel into the fire-box.

The side plates 14 mount a pair of opposed longitudinal supporting flanges 20 in the form of angle metal designed to support a fire-grate which is preferably made up of sections 21 so they may be readily removed 110 from the fire-box when desired. It is obvious that a grate arranged in a camp stove

will materially increase the efficiency of the stove.

The fire-box top or cover is made up of a pair of separably connected plates 22 of cast iron or the like, having the usual openings 23 closable through using ordinary lids 23' as shown. The rear end of each plate 22 is provided with an outlet or flue opening 24 having communication with a rigid removable smoke stack or flue pipe 25. The opposed ends of this smoke stack are provided with beads or shoulders 26 which serve to reliably secure slidable covers 27 in position over said ends. These covers 27 include flanges 28 which take over the beads or shoulders 26 and through forming a flange at one end of each cover there is assured positive connection between the smoke stack and covers. As shown, draft control is provided through adjustment of the top cover 27 when the stove is assembled. In mounting the smoke stack upon the fire-box, I secure to each top plate 22, a pair of spaced angle members 29 which take over the adjacent bead or shoulder 26. A handle 30 is secured to the smoke stack, providing means for carrying the stack within which the entire stove is packed for transportation. After the several side and top plates etc., have been packed in the smoke stack, the ends are closed by the heretofore mentioned covers 27. Supporting legs 31 are removably attachable to the base plates 10.

Manifestly, the construction shown is capable of considerable modification and such modification as may fall within the scope of my claims, I consider within the spirit of my invention.

I claim:

- 40 1. A collapsible camp stove comprising a knockdown fire-box, a rigid smoke stack, said fire-box being arrangeable in the smoke stack when knocked down, and cover plates removably attachable to the opposed ends 45 of the smoke stack.
2. A collapsible camp stove comprising a knockdown fire-box having a smoke-outlet, a rigid smoke-stack removably attachable over the smoke-outlet, a sectional separable 50 fire-grate arranged in the fire-box, said fire-box including a pair of inter-connected separable top plate sections, a pair of inter-

connected separable base plate sections and side and end members connecting the top and base plates.

3. A collapsible camp stove comprising a knockdown fire-box including a separably connected two-part top plate, a separably connected two-part base plate, side and end members connecting the top and base plates, 60 a pair of opposed supporting flanges arranged upon the inner faces of the side members, and a transversely divided fire grate resting upon the flanges.

4. A collapsible camp stove comprising a knockdown fire-box including a separably connected two-part top plate, a separably connected two-part base plate, side and end members connecting the top and base plates, 65 a pair of opposed supporting flanges arranged upon the inner faces of the side members, a transversely divided sectional fire-grate resting upon the flanges, and a pair of superposed fire doors arranged in one end.

5. A collapsible camp stove comprising a knockdown fire-box including a separably connected two-part top plate, a separably connected two-part base plate, side and end members connecting the top and base plates, 80 a pair of opposed supporting flanges arranged upon the inner faces of the side members, a transversely divided sectional fire-grate resting upon the flanges, a pair of superposed fire doors arranged in one end, and a smoke-stack disposed at the opposite end of the fire box and communicating with the interior through the top plate, said fire-box being collapsible for reception in the smoke stack.

6. In a collapsible camp stove, a fire-box comprising elongated two-part top and base plates, side and end members separately inter-connecting the plates, said top plate having openings at the meeting edges of the two parts, a grate spaced above the base plate, a pair of superposed doors at one end of the fire-box to permit access to the spaces above and below the grate, said top plate having an outlet opening near one end, and a smoke-stack over the opening.

In testimony whereof, I affix my signature.

HERMAN C. HOLL.
